HOBBING MACHINE

Otis E. Staples, Euclid, Ohio, assignor to The
Cleveland Hobbing Machine Company, Euclid,
Ohio, a corporation of Ohio

Application January 1, 1943, Serial No. 470,973

4 Claims. (Cl. 90—4)

The present invention relates to hobbing machines of the general type disclosed in my co-pending application Serial No. 410,744, filed September 13, 1941, now U. S. Patent No. 2,307-428, issued January 5, 1943.

The principal object of the invention is the provision of a novel improved hobbing machine of the type referred to, in which the vertical feed movement of the work head is or can be automatically interrupted prior to the time the rotation of the tool and work spindle is automatically stopped, thus making it possible to cut splines of equal length, which is impossible with the machine of the aforesaid application.

Further objects and advantages of the invention will be apparent to those skilled in the art to which the invention relates from the following description of the preferred embodiment described with reference to the accompanying drawings forming a part of this specification and in which:

Fig. 1 is a perspective view of a hobbing machine embodying the present invention;

Fig. 2 is a horizontal section with portions broken away and portions in elevation through the work head of the machine approximately on the line 2—2 of Fig. 3;

Fig. 3 is a section approximately on the line 3—3 of Fig. 2 with portions in elevation;

Fig. 4 is an enlarged front elevation of a part of the machine shown in Fig. 1;

Fig. 5 is a section with portions in elevation approximately on the line 5—5 of Fig. 4; and

Fig. 6 is a schematic wiring diagram of the machine.

For the most part the machine of the preferred embodiment herein described and illustrated is similar in construction to the machine disclosed in my aforesaid Patent No. 2,307,428, and therefore will not be herein shown and described in detail. Reference is made to said application for a complete disclosure of the parts of the machine not herein shown and described in detail.

Generally speaking, the machine shown comprises a base A having a vertical column B fixed thereto, a work head C slidably supported on vertically spaced pairs of vertical ways 8 and 9 on the column B, and a tool or hob head D adjustably supported on horizontal ways 10 intermediate the ways 8 and 9. The tool and work spindles are geared together and driven from a reversible electric motor 11 (see wiring diagram) located within the column B and herein-after referred to as the cut motor. A relative

feed movement between the spindles is effected by moving the work head C vertically through the medium of a lead screw 12 operatively connected to the drive for the tool and work spindles.

Means in the form of a high speed reversible electric motor 13 (see wiring diagram), herein-after referred to as the traverse motor, operatively connected to the nut located within a housing 14 and with which nut the lead screw 12 cooperates, is provided for rapidly elevating or lowering the work head C, as the case may be, to quickly bring the work blank W up to the hob H at the beginning of the cycle of operations and to return the work head to its starting position after the work has been cut and removed. The traverse motor is also housed within the column B. In the embodiment shown, the work W is adapted to be supported between a suitable chuck 15 fixed to the upper end of the work spindle 16 and a center 17 carried by a tailstock 18 slidably supported on vertical ways 19 on the work head C.

The tool and work spindles are geared together and operatively connected to the cut motor by gearing including a horizontal shaft 20 rotatively supported in the work head C and projecting forwardly through a partition 21 in the work head C and into a gear box or compartment, designated generally by the reference character 22. The shaft 20 is operatively connected to a horizontal shaft 23 through the medium of work spindle drive change gears E, the driving and driven gears 24 and 25 of which are keyed to the ends of the shafts 20 and 23, respectively. The shaft 23 is rotatably supported in an adjustable cradle 26 and is provided with a worm 27 continuously in mesh with a worm wheel 28 keyed to the work spindle 16.

To effect the relative feed movement between the tool and work the work head C is moved upwardly during the cutting operation in timed relation to the rotation of the tool and work spindles by the lead screw 12 previously referred to. The lead screw is adapted to be rotated from the work spindle drive by a worm wheel 30 keyed to the upper end thereof, which worm wheel is continuously in mesh with a worm 31 rotatably supported on a shaft 32 and fixed to one element 33 of a toothed clutch, designated generally as F, the other or driving element 34 of which is slidably splined to the shaft 32. The shaft 32, like the shafts 20 and 23, projects through the partition 21 and into the gear box 22 within which it is operatively connected to the

shaft 23 by the feed change gears G, the driving and driven gears 35 and 36, respectively, of which are fixed to the shafts 23 and 32, respectively. For the purposes of permitting the use of various change gears, idlers, etc., in the work spindle drive change gears E and the feed change gears G, suitable spiders or gear supporting members 37 and 38 are provided.

The clutch F is engaged and disengaged to connect and disconnect the feed lead screw 12 to and from the drive for the tool and work spindles by shifting or sliding the clutch element 34 to the left or right, respectively, as viewed in Fig. 2. The purpose of the clutch F will be hereinafter apparent from the resumé of the operation of the machine. The clutch element 34 is provided with an external cylindrical groove within which the lower end of a yoke member 40 engages. The yoke member 40 is pivotally connected for rotation about a vertical axis to the projecting end of a lever 41 fixed to the upper end of a vertical shaft 42, the lower end of which projects through the work head frame and has fixed thereto a lever 43.

The lever 43 is operatively connected to a 25 slideable member or rod 44 by a link 45, the length of which can be adjusted, and opposite ends of which link are bifurcated and pivotally connected to the lever 43 and the rod 44 by pivot pins 46 and 47, respectively. The rod 44 is slidably supported in a horizontal cylindrical aperture 48 in a housing or member 49 fixed to the work head C by screws 50 adjacent the left-hand bottom way 8, and is continuously urged to the right, as viewed in Fig. 5, by a compression spring 51 interposed between a shoulder 52 on the rod 44 formed by the reduced right-hand end thereof and a tubular member 53 threaded into the right-hand end of the aperture 48. The reduced end of the rod 44 extends through the central aperture of the tubular member 53. The rod 44 is adapted to be shifted towards the right, as viewed in Fig. 5, by a hand lever 54 fixed to the left-hand end of a short shaft 55 rotatably supported in a boss 56 on the upper end of a bracket 57 fixed to the member 49. The opposite end of the shaft 55 carries a lever 58 also fixed thereto, the lower forked end of which lever is connected to the rear end of the rod 44 by a pin 59.

When the rod 44 is moved to the right as viewed in Fig. 5 an amount sufficient to engage the clutch F, it is adapted to be held in that position by a latch or bolt 60 slidably supported in a vertical aperture 61, the upper end of which bolt is adapted to engage in a suitable aperture 62 in the rod 44. The bolt 60 is continuously urged in an upward direction by a compression spring 63 interposed between the lower end of the bolt proper and the upper end of a member 64 threaded into the lower end of the aperture 61. The member 64 has a central aperture through which a rod 65 connected to the lower end of the bolt proper projects. The lower end of the rod 65 is bifurcated and pivotally connected to a pivoted bar 66 by a pin 67. The front end of the bar 66 is pivotally supported on a bolt 69 fixed in a downwardly projecting member 68 while the other end thereof projects towards the rear of the machine where it is adapted to be engaged by a stop 70 adjustable along a rod or bar 71 fixed to the column B in a suitable manner. The construction is such that when the rear end of the bar 66 engages the stop 70 incident to the vertical movement of the work head C, the bar 66 is moved about its pivot 69 and the upper

end of the bolt 60 withdrawn from the aperture 62 whereupon the rod 44 moves to its left-hand position under the influence of the spring 51, thus disengaging the clutch F.

After a work blank W is positioned in the work head, the machine is started by pushing a start push button switch 83 located on a switch panel 84 mounted on the side of the machine, whereupon the traverse motor 13 operates to rotate the nut with which the lead screw 12 engages at a high rate of speed and in such a direction that the work is rapidly moved toward the hob H. Just prior to the time the work W engages the hob H a switch 85 located on the left-hand side of the column B is actuated by an adjustable stop 86 carried by the work head C; stopping the traverse motor 13 and starting the cut motor 11.

In the event the snap switch 91 located on the switch panel 84 is opened the up and down limits of movement of the work head C are automatically controlled by an electric switch 87 actuated by adjustable stops 88 and 89 also carried by the work head C. The stop 88 controls the downward limit of movement and the stop 89 the upward limit of movement of the work head C.

In the event the snap switch 91 is closed, the cut motor 11 is not stopped upon actuation of the limit switch 87 by the stop 89 but is manually controlled by the stop switch 92 which is actuated by the operator after the feed movement has been interrupted by disengagement of the clutch F. According to the provisions of the present invention, the work makes at least one revolution after the clutch F has been disengaged so that the splines, etc., are all the same length.

After the blank has been cut and removed, the work head C is returned to its starting position 40 by again depressing the start push button switch 83. For safety, a normally closed travel limit switch 90 is provided, see wiring diagram. The limit switch 90 is located on the right-hand side of the column B and for that reason is not shown 45 in Fig. 1 of the drawings, but is so mounted and adapted to be opened by a fixed stop carried by the work head C that the work head C cannot be raised high enough to damage the machine even though the other switches fail.

50 The particular machine shown herein can be operated either in exactly the same manner as the machine disclosed in my aforesaid application Serial No. 410,744, by opening the snap switch 91, in which event the clutch F does not disengage 55 as the stop 89 is set to actuate the switch 87 before the lever 66 engages the stop 70. The direction in which the cycle of operations is effected is controlled by drum controllers I and J also mounted on the switch panel 84. The drum controller I 60 has two positions, designated "up" and "down," respectively. When the drum controller I is set in the "up" position, the circuits to the switches 85, 87, etc., are connected to execute the cycle of operations wherein the work head C moves in an 65 upward direction to effect the feed, and vice versa. The drum controller J has two positions, designated "forward" and "reverse," respectively. When the controller is set in the "forward" position, the direction of rotation of the hob spindle 70 is such that the hob moves down in front, that is in a clockwise direction as viewed in Fig. 1, and vice versa. Since the feed can be effected in either direction of movement of the work head C and since the cut motor which drives the hob can 75 be reversed, it will be apparent that either "climb"

hobbing or "conventional" hobbing can be effected in either direction merely by setting the drum controllers I and J in the selected positions and either inserting or removing an idler gear in the spindle drive change gears E or the feed change gears G, or in other words, by so selecting the change gears that the feed is in the proper direction.

The cut and traverse motors are preferably of the reversible three-phase alternating current type and are adapted to be connected to and disconnected from the power lines 95, 96 and 97 by solenoid-actuated motor controllers 93 and 94 of commercial design mounted on the controller panel 98. The construction and operation of these controllers are well understood in the art and will not be described in detail. The controller panel 98 is suitably housed within the column B and the wires employed in connecting the motors 11 and 13 thereto are designated by the reference characters 100, 101 and 102; and 103, 104 and 105, respectively.

Operation

In the embodiment shown, the clutch F functions only when the cycle of operations is such that the feed is effected by an upward movement of the work head C. Since this cycle of operations is the only one which is materially different from that disclosed in the aforesaid application, it alone will be described in detail. With the drum controller I set in "up" position, the drum controller J set in "forward" position, and the change gears as shown in the drawings, the machine is arranged to go through its cycle of operations wherein the feed is effected by an upward movement of the work head C, with the hob rotating clockwise as viewed in Fig. 1; in other words, the cutting operation will be conventional. At the beginning of the cycle of operations the work head C is in its "down" or lower position. After the operator has positioned a work blank in the work head C, the start push button switch 83 is depressed, opening the normally closed contacts 107, 108 and closing the normally open contacts 109, 110; 111, 112. The closing of the contacts 111 and 112 establishes a circuit from the line 97 through the overtravel limit switch 90, wire 113, normally closed stop push button switch 92, wire 114, contacts 111, 112, wire 115, operating solenoid 116 of relay 117, wire 118, contacts 119, 120 of drum controller I, wire 121, contacts 122, 123 of switch 87, to line 96, energizing the solenoid 116 of relay 117. Energization of the operating solenoid 116 of relay 117 closes the normally open contacts 124, 125; 126, 127; 128, 129 and opens the normally closed contacts 130, 131 thereof.

The closing of contacts 124, 125 establishes a circuit from the line 97 through the overtravel limit switch 90, wire 113, stop push button switch 92, wire 114, contacts 124, 125, wire 136, operating solenoid 137 of motor controller 94, wire 138, contacts 139, 140 of drum controller I, wire 141, contacts 142, 143 of limit switch 85, wire 118, contacts 119, 120 of drum controller I, wire 121, contacts 122, 123 of limit switch 87 to line 96, energizing the solenoid 137 and connecting the motor 13 to the power lines 95, 96 and 97, in such a manner that the motor operates in a direction to raise the work head C. The wires 103 and 104 previously referred to are connected to the motor 13 by contacts 144, 145; 146, 147 of drum controller I and wires 148 and 149.

Energization of the operating solenoid 137, in

addition to closing the main power contacts 150, 151; 152, 153; 154, 155; which connect the motor 13 to the power lines, closes auxiliary contacts 156, 157, establishing a holding circuit for maintaining the solenoid 137 energized even though the relay 117 may subsequently be deenergized. When the stop push button switch 83 is released the circuit for relay 117 is opened upon the opening of contacts 111 and 112 but is immediately reestablished through contacts 107, 108, the closing of which establishes a circuit from wire 114 through auxiliary contacts 156, 157, wire 136, contacts 107, 108, wire 115, operating solenoid 116, etc. to line 96. The reclosing of contacts 124, 125 which are in parallel circuit with contacts 156, 157 maintains the operating solenoid 116 of relay 117 energized even though contacts 156, 157 subsequently open, as hereinafter mentioned.

The travel motor 13 continues to operate raising the work head C until just prior to the engagement of the work W with the hob H, at which time the stop 86 on the work head C actuates the switch 85 opening the previously closed contacts 142, 143 thereof and closing the open contacts 158, 159; 160, 161. The opening of contacts 142, 143 breaks the circuit of the solenoid 137 allowing contacts 150, 151; 152, 153; 154, 155; 156, 157 to open stopping the traverse motor 13.

The closing of contacts 160, 161 establishes a circuit for the operating solenoid 162 of motor controller 93 from the line 97, through the overtravel limit switch 90, wire 113, stop push button 92, wire 114, contacts 124, 125 of relay 117, wire 136, contacts 107, 108 of start push button switch 83, wire 115, operating solenoid 162, wire 163, contacts 164, 165 of drum controller I, wire 166 contacts 160, 161 of limit switch 85, wire 118, contacts 119, 120 of drum controller I, wire 121, contacts 122, 123 of limit switch 87 to line 96. Energization of the operating solenoid 162 of motor controller 93 closes the main power contacts 170, 171; 172, 173; 174, 175 and connects the cut motor 11 to the power lines 95, 96 and 97 through the drum controller J by means of contacts 176, 177; 178, 179 and wires 180, 181.

The work head C continues to rise under the operation of the cut motor 11 at a feed rate and as it approaches its upper limit of travel, the stop 89 actuates the limit switch 87 to open the previously closed contacts 122, 123 and close the previously open contacts 182 and 183. The opening of contacts 122, 123 of limit switch 87 opens the circuit for the operating solenoid 162 previously referred to. However, the solenoid is maintained energized by a circuit through contacts 128, 129 of relay 117, wire 174, contacts 158, 159 of limit switch 85, wire 185, snap switch 91, which is now closed, to line 96. The operating solenoid 116 of relay 117 is maintained energized by a circuit through contacts 126, 127, wire 185 and snap switch 91 to line 96.

The cut motor 11 continues to operate, raising the work head C at a feed rate until the clutch F is disengaged by the engagement of the arm 66 with the stop 70 in a manner hereinbefore described. Upon disengagement of the clutch F, the feed stops. However, the cut motor continues to operate, rotating the tool and work spindles in predetermined relation. After the work spindle has made at least one complete rotation, the operator pushes the stop push button 92, deenergizing the solenoid 116 of relay 117, opening contacts 124, 125; 126, 127; 128, 129 of said relay the contacts 128, 129 which in turn open the circuit to the operating solenoid 162,

disconnecting the cut motor 11 from the power lines 95, 96 and 97.

In the event the snap switch 91 is open, which would be the case if the machine was operated in accordance with the cycle disclosed in my aforesaid application, the cut motor would stop upon actuation of the limit switch 87 by the stop 89 since the opening of the contacts 122, 123 thereof would break not only the circuit to the operating solenoid 116 of relay 117, but also the 10 circuit to the operating solenoid 162 of motor controller 93.

The finished work blank is now removed from the work head C and the start push button switch 83 again depressed to actuate the rapid 15 traverse or travel motor 13 in a reverse direction to lower the work head C to its starting position. When the start push button switch 83 is depressed for the second time, a circuit is established from the line 97, through the overtravel limit switch 90, wire 113, stop push button switch 92, wire 114, contacts 109, 110 of start push button switch 83, wire 186, contacts 130, 131 of relay 117, wire 187, operating solenoid 188 of motor controller 94, wire 189, contacts 190, 191 of drum controller I, wire 192, contacts 182, 183 of switch 87 to line 96.

Energization of the solenoid 188 closes the main contacts 193, 194, 195, 196, 197, 198 associated therewith, connecting the rapid traverse or travel motor 13 to the power lines in such a manner that it operates in the reverse direction, that is, in a direction to lower the work head C. Simultaneously with the closing of the contacts which connect the motor 13 with the power lines, auxiliary contacts 200, 201 are closed, establishing a holding circuit for the solenoid 188 after the start push button switch 83 is released. This holding circuit is from the line 97 through the overtravel limit switch 90, wire 113, stop push button switch 92, wire 114, contacts 200, 201, wire 187, solenoid 188, wire 189, contacts 190, 191 of drum controller I, wire 192, contacts 182, 183 of switch 87 to line 96.

As the work head C drops, the adjustable stop 86 thereon returns the switch 85 to its original position as the stop passes the switch. This re-opens the contacts 158, 159; 160, 161 and closes the contacts 142, 143, thus again setting up the circuit with respect to the cut motor 11 which existed at the beginning of the cycle of operations. The work head C continues to move down until the switch 87 is tripped by the adjustable stop 88 carried by the work head C. This re-opens the contacts 182, 183, stopping the rapid traverse or travel motor 13 and recloses the contacts 122, 123, returning the circuit to the rapid traverse or cut motor 13 to its original condition. After a new work blank is inserted in the work head C, the cycle of operations of the machine can be repeated by again pressing the start push button switch 83.

From the foregoing description of the preferred embodiment of the invention, it will be apparent that the objects heretofore enumerated and others have been accomplished and that a new and improved machine of the character referred to has been provided. While the preferred embodiment of the invention has been described with considerable detail, it is to be understood that the invention is not limited to the particular construction shown. For example, in the embodiment described the clutch F functions only when the feed is effected by a vertical movement of the work head. However, the machine shown

could readily be modified so that the clutch F would function in either direction and irrespective of whether the cutting operation was "conventional" or "climb." It is my intention to hereby cover all adaptations, modifications and uses of the invention herein disclosed which come within the practice of those skilled in the art to which the invention relates.

Having thus described my invention, I claim:

1. A hobbing machine of the character described comprising: a frame; a work spindle; means for rotatably supporting said work spindle; a hob or tool spindle; means for rotatably supporting said hob or tool spindle; a lead screw and a cooperating nut for producing relative movement between said work spindle and said tool spindle; a first means for rotating said spindles and for producing relative rotation between said lead screw and said nut to effect a relative movement between said spindles at a feed rate; a second means for producing relative rotation between said lead screw and said nut in opposite directions to effect a relative movement between said spindles at a rapid traverse rate; means for effecting the operation of said second means whereupon relative movement between said spindles is produced in one direction at a rapid traverse rate; means for automatically initiating the operation of said first means and discontinuing the operation of said second means upon said spindles reaching a predetermined relative position whereupon the relative movement between said spindles is continued but at a feed rate; means for automatically discontinuing the relative rotation between said lead screw and nut upon said spindles reaching a second predetermined relative position without discontinuing the rotation of said spindles; means for discontinuing the operation of said first means after a predetermined period during which the work spindle makes at least one complete revolution; means for effecting or initiating the operation of said second means but in such a manner that it operates in the reverse direction whereupon relative movement between said spindles is produced in the opposite direction at a rapid traverse rate; and means for automatically discontinuing the operation of said second means upon said spindles reaching their starting or initial relative position.

2. A hobbing machine of the character described comprising: a frame; a work spindle; means for rotatably supporting said work spindle; a hob or tool spindle; means for rotatably supporting said hob or tool spindle; a lead screw and a cooperating nut for producing relative movement between said spindles; an electric motor for rotating said spindles and for producing relative rotation between said lead screw and said nut to effect a relative movement between said spindles at a feed rate; a reversible electric motor for producing relative rotation between said lead screw and said nut to effect a relative movement between said spindles at a rapid traverse rate; means for operatively connecting the second mentioned electric motor to a source of power whereupon relative movement between said spindles is produced in one direction at a rapid traverse rate; means for automatically connecting the first mentioned motor to the source of power and disconnecting the second mentioned motor from the source of power upon said spindles reaching a predetermined relative position whereupon the relative movement between said spindles is continued but at a feed rate;

means for automatically interrupting the drive between said first mentioned electric motor and said lead screw upon said spindles reaching a second predetermined relative position; means for disconnecting the first mentioned motor from the source of power after the lapse of a predetermined period within which said work spindle makes at least one complete revolution; means for connecting the second mentioned motor to the source of power but in such a manner that it operates in the reverse direction whereupon relative movement between said spindles is produced in the opposite direction at a rapid traverse rate; and means for automatically disconnecting said second mentioned motor from the source of power upon said spindles reaching their starting or initial relative position.

3. A hobbing machine of the character described comprising: a frame; a vertical work spindle; means for rotatably supporting said work spindle; a hob or tool spindle, means for rotatably supporting said hob or tool spindle; a lead screw and a cooperating nut for producing relative movement between said spindles, an electric motor for rotating said spindles and for producing relative rotation between said lead screw and said nut to effect a relative movement between said spindles at a feed rate in a vertical direction; a reversible electric motor for producing relative rotation between said lead screw and said nut to effect a relative movement between said spindles at a rapid traverse rate; means for operatively connecting said reversible electric motor to a source of power whereupon relative movement between said spindles is produced in one direction at a rapid traverse rate; means for automatically connecting the first mentioned motor to the source of power and disconnecting said reversible motor from the source of power upon said spindles reaching a predetermined relative position whereupon the relative movement between said spindles is continued but at a feed rate; means for automatically interrupting the drive between said first mentioned electric motor and said lead screw upon said spindles reaching a second predetermined relative position; means for disconnecting the first mentioned motor from the source of power after the lapse of a predetermined period within which said work spindle makes at least one complete revolution; means for

connecting said reversible motor to the source of power but in such a manner that it operates in the reverse direction whereupon relative movement between said spindles is produced in the opposite direction at a rapid traverse rate; and means for automatically disconnecting said second mentioned motor from the source of power upon said spindles reaching their starting or initial relative position.

- 10 4. A hobbing machine of the character described comprising: a frame; a work head slidably supported for movement along said frame; a vertical work spindle rotatably supported by said work head, a hob or tool spindle rotatably supported by said frame; a lead screw and a cooperating nut for moving said work head relative to said tool spindle; an electric motor for rotating said spindles and for producing relative rotation between said lead screw and said nut to move said work head at a feed rate; a reversible electric motor for producing relative rotation between said lead screw and said nut in opposite directions to move said work head at a rapid traverse rate; means for operatively connecting the second mentioned electric motor to a source of power whereupon said work head is moved in one direction at a rapid traverse rate; means for automatically connecting the first mentioned motor to the source of power and disconnecting the second mentioned motor from the source of power upon said work head reaching a predetermined position whereupon the movement of the work head continues but at a feed rate; means for automatically interrupting the drive between said first mentioned electric motor and said lead screw upon said spindle reaching a second predetermined relative position; means for disconnecting the first mentioned motor from the source of power after the lapse of a predetermined period within which said work spindle makes at least one complete revolution; means for connecting the second mentioned motor to the source of power but in such a manner that it operates in the reverse direction whereupon the work head is moved in the opposite direction at a rapid traverse rate; and means for automatically disconnecting said second mentioned motor from the source of power upon said work head reaching its starting or initial position.

OTIS E. STAPLES.
